Inventor
Albert H. Potter, by
Cimber and Quarell, his Attys.

UNITED STATES PATENT OFFICE.

ALBERT H. POTTER, OF GENEVA, SWITZERLAND, ASSIGNOR, BY DIRECT AND MESNE ASSIGNMENTS, TO THE NEW HAVEN WATCH COMPANY, OF NEW JERSEY.

COMBINED WATCH-CASE AND MOVEMENT-PLATE.

SPECIFICATION forming part of Letters Patent No. 360,477, dated April 5, 1887.

Application filed July 2, 1886. Renewed March 1, 1887. Serial No. 229,375. (No model.)

To all whom it may concern.

Be it known that I, ALBERT H. POTTER, of Geneva, in the Republic of Switzerland, have invented certain new and useful Improvements 5 in Watches; and I do hereby declare that the following is a full, clear, and exact description thereof, reference being had to the accompanying drawings, in which—

Figures 1 and 2 are perspective views of my 10 combined case-center and front movement-plate from opposite sides. Figs. 3 and 4 are like views of my combined case-center, case-back, and rear movement-plate from opposite sides; and Figs. 5 and 6 are central sections of 15 my completed watch, and show, respectively, the construction where a separate case-back is employed and where the same is omitted.

Letters of like name and kind refer to like parts in each of the figures.

20 This invention relates to certain improvements in watches which are covered by two previously-filed applications for patents, Serial Nos. 168,586 and 196,502, and has for its object the providing of a watch having the construction described, with an exterior of gold or other 25 precious metal; to which end my said invention consists, principally, as an improvement in watches, in a combined movement-plate and case-center constructed in one piece from base 30 metal and having the periphery of the case-center portion covered by a shell of precious metal which is superimposed upon and secured to the same, substantially as and for the purpose hereinafter specified.

35 It consists, further, as an improvement in watches, in a combined movement-plate and case-center constructed in one piece from base metal and having the periphery of the case-center portion covered by a superimposed 40 plate of precious metal, in combination with a bezel and a case-back which are constructed from precious metal and are fitted to and adapted to engage with said case-center portion, substantially as and for the purpose here- 45 inafter shown.

It consists, further, as an improvement in 45 watches, in a combined movement-plate, case-center, and case-back which are constructed in one piece from base metal and have the

outer surfaces of the case-center and case-back 50 portions covered by a superimposed and attached plate of precious metal, substantially as and for the purpose hereinafter set forth.

It consists, finally, as an improvement in 55 watches, in a combined movement-plate, case-center, and case-back which are constructed in one piece from base metal and have the outer surfaces of the case-center and case-back portions covered by a superimposed and attached plate of precious metal, in combination 60 with a bezel which is constructed from precious metal and is adapted to engage with said case-center portion, substantially as and for the purpose hereinafter shown and described.

In the carrying of my invention into practice 65 I employ a metal plate, A, which, by dies or other suitable means, has its edge turned upward at a right angle to its face, so as to form of the same an annular flange, a. The plate A forms one of the movement-plates of 70 a watch, and the flange a the case-center of the same. As shown in Figs. 1, 2, and 5, said plate constitutes the front movement-plate, and has its outer edge adapted to receive a dial, B, and is provided with a peripheral rabbet, a', 75 that may be engaged by an ordinary glass bezel, C, while within the corners of the edge of said case-center portion are formed an outer and an inner rabbet, a² and a³, respectively, for the reception of a case-back, D, and a rear 80 movement-plate, E.

When the plate A is used for a rear movement-plate, as shown in Figs. 3, 4, and 6, its outer face forms the case-back, the plate E constitutes the front movement-plate, and the 85 bezel C engages with the rabbet a².

The plate A is constructed from brass, 90 nickel, or other cheap or base metal, and for cheap watches will have its outer surface, together with the surfaces of the bezel and back, when the latter is used, polished or electro-plated in the usual way; but for finer grades of watches, where silver or gold cases are required, the bezel (or bezel and back) for the same is (or are) constructed wholly from such precious 95 metal, and over the exposed surface of the base metal is placed a shell, a⁴, which is made to conform to and fit closely upon the same, and

is secured in place by the ordinary process of "sweating" with soft solder. This is done before the rabbets are cut, by which means the fine metal will extend to and be impinged upon by the engaging-edge of the bezel, (or case-back,) so as to cause the entire exterior surface of the case to present a surface of fine metal.

After the case-center is completed, a pend-
10 ant, F, of any usual construction, is secured within a radial opening, a⁵, that is provided for its reception.

The combined movement-plate and case-cen-
15 ter shown is not claimed, broadly, herein, as
the same is covered by a separate application
for Patent, Serial No. 168,586.

Having thus described my invention, what I
claim is—

1. As an improvement in watches, a com-
20 bined movement-plate and case-center con-
structed in one piece from base metal and hav-
ing the periphery of the case-center portion
covered by a shell of precious metal which is
superimposed upon and secured to the same,
25 substantially as and for the purpose specified.

2. As an improvement in watches, a com-
bined movement-plate and case-center con-
structed in one piece from base metal and hav-
ing the periphery of the case-center portion
30 covered by a superimposed plate of precious

metal, in combination with a bezel and a case-
back which are constructed from precious
metal and are fitted to and adapted to engage
with said case-center portion, substantially as
and for the purpose shown.

3. As an improvement in watches, a com-
bined movement-plate, case-center, and case-
back which are constructed in one piece from
base metal and have the outer surfaces of the
case-center and case-back portions covered by
40 a superimposed and attached plate of precious
metal, substantially as and for the purpose set
forth.

4. As an improvement in watches, a com-
bined movement-plate, case-center, and case-
back which are constructed in one piece from
base metal and have the outer surfaces of the
case-center and case-back portions covered by
45 a superimposed and attached plate of precious
metal, in combination with a bezel which is
constructed from precious metal and is adapted
to engage with said case-center portion, sub-
stantially as and for the purpose shown and
described.

In testimony whereof I hereunto set my hand
this 30th day of June, A. D. 1886.

ALBERT H. POTTER.
